UNITED STATES PATENT OFFICE.

JOHN F. ISBELL, OF LOS ANGELES, CALIFORNIA, ASSIGNOR TO ORREN ALLEN, OF DENVER, COLORADO.

CONCENTRATOR.

1,169,959.

Specification of Letters Patent.

Patented Feb. 1, 1916.

Application filed April 6, 1912. Serial No. 688,855.

To all whom it may concern:

Be it known that I, JOHN F. ISBELL, a citizen of the United States, residing at Los Angeles, in the county of Los Angeles, State of California, have invented new and useful Improvements in Concentrators, of which the following is a specification.

This invention relates to a separating machine for ores and the like in suspension in water in the form of a pulp and particularly to a machine adapted for concentrating slimes; and it is the prime object of my invention to provide a simple mechanism whereby a high metal saving efficiency may be attained by the separation and saving of those portions ordinarily known as slimes.

In my invention I carry out the operation of concentrating and separating valuable minerals from their gangue in such manner as to save and separate from the tailings that part of the materials usually known as slimes; that is, that part which, on account of its peculiar physical characteristics, is usually very difficult to effectively handle. The separating is carried out on a table carrying a comparatively thick bed of material in which the upper portions protect the lower valuable strata; that is, the depth of flow makes the lower strata run smoothly, evenly and quietly and allows the values to be separated and concentrated. The result is a thorough concentration and separation of the valuable minerals, the slimes, from the gangue or tailings.

My invention consists fundamentally in a device for carrying out the following described mechanical operations. The pulp is first fed on to the concentrating table and is so handled and manipulated that the natural gravitational stratification is allowed to take place, the heavier and finer particles sinking to the bottom and the lighter and the coarser particles arranging themselves above. This function I would call vertical separation or concentration. The next step in the method of operation carried out by my machine is the separation or concentration of the material in a horizontal direction; that is, means are provided for moving the lower and heavier portions of the stratified material in one direction while the upper lighter portions are allowed to move in another direction. The result of this operation is that the heavier and finer materials are

concentrated with respect to both vertical and horizontal motion. The final operation is that of removing certain portions of the material, preferably the lower strata thereof, at the points where the heavier values have been concentrated by this vertical and horizontal concentrating movement. In practice, it might be said that vertical and horizontal movements are substantially simultaneous. Pulp is fed on to the table and the action of concentration and removal of the values is continuous. In its preferred form, the machine which I now use to accomplish this method of concentration consists of a table with a distributing or concentrating upper surface, the table being elongate and slightly higher at the head or feed end than at the tail or discharge end. At the tail end I provide a slight raise which serves to hold an even bed of pulp on the table and to prevent excessive velocity of flow. The table is moved to and fro by a suitable mechanism so as to continuously keep the solid material in motion, and this continuous movement allows the heavier materials to take up their position forming the lower strata. Suitable riffles are supplied on the table which catch only the lower strata of the material. These riffles are placed at a slight inclination to the direction of slope of the table, so that, in addition to the longitudinal movement of all the materials, the lower and heavier portions are given a transverse horizontal movement which gradually concentrates all of the values along a single concentration line longitudinal of the table. Along this concentration line I arrange a suitable number of outlet devices, being arrangements for removing from the table the lower strata of the material on the concentration line without drawing out any of the upper strata. This means that the lower strata on the concentration line must be withdrawn from the table without disturbing the upper strata and without forming a stream which might change the flow of materials over the table; and I will describe in detail herein-after a form of device, being the now preferred form of this portion of my invention, which accomplishes this operation efficiently.

It will be understood that I intend throughout this specification the term "riffles" to include any device of that nature; 110

whether made by building up or cutting out grooves or corrugations, and of whatever cross-sectional configuration.

I will proceed to a detailed description 5 of my now preferred form of device embodying my invention, the same being shown in the accompanying drawings, in which:

Figure 1 is a plan view of my improved 10 concentrator. Fig. 2 is a vertical longitudinal section of the same taken on line 2—2 of Fig. 1. Fig. 3 is an enlarged cross section taken as indicated by line 3—3 of Fig. 1. Fig. 4 is a detail perspective of one of 15 the devices for removing the lower strata of values from the table. Fig. 5 is a longitudinal vertical section of the same. Fig. 6 is a perspective showing the arrangement of 20 ripples on the table surface and indicating the flow of the different strata of material thereon. Fig. 7 is a section showing a preferred form of table vibrating mechanism.

In the drawings 5 designates a suitable 25 base frame which may be constructed in any desired manner, as the particulars of this construction and of the general mounting of the table do not enter directly into my invention. Upon this base frame 5 I prefer to suitably mount sheaves 6 upon which bearing rods 7 formed as pipes are supported so that they may move longitudinally. Bearing rods 7 are secured by suitable brackets or bearings 8 to the under side of table structure 9. This arrangement 30 provides a structure for supporting the table allowing smooth to and fro motion without objectionable vibration or quivering. Table structure 9 is comprised mainly in a surface member 10 supported on a suitable table framework and surrounded preferably upon two sides and its upper end by suitable walls 11 and 12 for retaining liquid upon the table. Surface member 10 may be covered with a suitable liquid proof covering material, as shown at 13 in Fig. 5.

In Fig. 1 I have shown the plan of a table 50 consisting of two distinct portions; but each portion is complete in itself, and I only construct a table in this manner for mechanical and economic reasons. In this case the table top is divided by a longitudinal central wall 11^a and the table surface on each side of this longitudinal central wall is identical with that on the other side. 55 Upon the surface member of the table I preferably place two series of parallel ripples 20, these ripples extending generally longitudinally of the table but having a slight inward inclination toward the center 60 of each table surface. The central longitudinal line on the table surface I will call the concentrating line; for it is along these lines that the values are concentrated and removed. (From the following described 65 operation it will be seen that each series

of parallel ripples on each side of the concentrating line has an action identical with the other; so far as the principles of action are concerned a single series of ripples inclined toward a concentrating line at one 70 side includes my invention as well as both series and a central concentrating line.) The table surface member 10 may be slightly higher along its central concentrating line than along other portions; but the slope 75 from the concentrating line to the outer longitudinal edges of the table is comparatively slight, if any is used at all. The ripples 20 are preferably higher at their ends adjacent the concentrating line than at their 80 ends at the outer edges of the table to accommodate the gradually increasing strata of values. This is shown most clearly in Fig. 3; and in a practical table now in use I use successfully ripples which are about one- 85 eighth of an inch high at their outer end and five-sixteenths of an inch at their inner or concentrating line end. The head end of the table is to the right in Fig. 1; and the table as a whole slopes slightly downwardly to the tail end, to the left in that figure. It will be seen that the ripples thus extend downwardly longitudinally on the table and diagonally inwardly toward the concentrating line. When material is delivered to the table, it will slowly flow down longitudinally of the table; and, if the table surface is higher along the concentrating line than along the edges, the flow will be greater at the edges and the material will 90 be deeper there. The action of the table, however, can be maintained without having the surface high along the concentrating line. The lower, or tail, end of the table is banked up slightly, as at 100, to hold an 105 evenly flowing bed of pulp over the ripples. 110

It will be seen that the ripples extend inwardly to points adjacent the concentrating line and that sufficient space is left between their ends for the flow of material directly 115 down the concentrating line of the table without of necessity passing over the ripples. This, as will be later explained, is true of the heavier materials carrying the values. At suitable intervals down the concentrating line of the table I place discharge or outlet members 25 of the general configuration and construction shown in Figs. 4 and 5. These members 25 are made of such angular elongated shape that their edges 120 form continuations of two approaching ripples, the ripples at this point being allowed to abut the outlet device as is best shown in Figs. 4 and 5. As before explained, these outlet devices are designed particularly to 125 remove only the lower strata of the material over the concentrating line of the table and to remove it in such manner as to not disturb the other materials on the table. I preferably provide a suitable body 30 of 130

elongate pointed plan with a hollow interior 31 surrounded by suitable side walls but having a bottom wall 32 only over a portion, the portion nearer the tail end of the table, 5 of its bottom. This bottom wall 32 has a sharply beveled edge 33 over which the material must pass in order to pass down outlet pipe 34. The portion of the interior 31 otherwise bottomless is covered by a suitable shelf 35 preferably inclined in the direction shown in Fig. 5 and preferably having a small aperture 36 at its lower or forward end, through which aperture a small amount of water may pass. Water is delivered independently to this outlet device 10 through a small tube 37, or any other convenient means, connecting with a water supply pipe 38. The water falls directly on shelf 35 and passes partly through opening 36 and partly over the rear edge of shelf 35 directly above the beveled edge 33 of bottom 32. This water, comparatively small in amount, serves only to prevent the choking of the opening at 38 and to keep the pulp 15 moving freely over into the discharge pipe 34. Extending out forwardly of the body 30 there is a suitable plane member 40 preferably parallel to the table surface, member 40 forming constructively a continuation 20 of shelf 35. This member 40 is supported by suitable side supports 41 preferably formed integrally with the body 30; and it also preferably has a pointed forward or upper end projecting into the downwardly 25 moving stream of material.

The height of member 40, the height of shelf 35 and of bottom 32 will depend entirely upon the character of material being handled. But the arrangement is always 30 such that only the lower strata of heavier and finer particles will pass under the plane member 40, which may be termed a pulp divider, and into the outlet pipe 34. The upper or interior surface of bottom wall 32 35 is preferably equal in height from the table surface to the height of the under surface of member 40, so that the strata of pulp passing under the member 40 will only flow over the beveled edge 33 of bottom wall 32 40 as fast as the pulp elsewhere on the table is flowing downwardly. This provides that there shall be no undue suction under the member 40 to draw in the upper strata of the material and that only the strata which 45 normally are below the lower surface of member 40 will pass into the discharge pipe 34. Discharge pipe 34 is of ample capacity to freely carry off all the pulp which will 50 pass through the opening beneath the member 40 and through the opening at 38, so that the strata beneath member 40 may 55 freely flow downwardly longitudinally of the table and be discharged therefrom. This is one of the important features of my 60 invention; that the material removed from 65

the lower strata of concentration is removed freely without either causing an acceleration of flow at that point or a retard or bulging up of the strata. Either of these undesired effects would materially diminish 70 the efficiency of concentration and separation.

In Fig. 7 I have shown a typical means of moving the table longitudinally to and fro. Although, so far as my invention is 75 directly concerned, other mechanisms will suffice, the mechanism about to be described accomplishes precisely the desired movement for hastening the flow of material down the table without diminishing the opportunity for withholding the values 80 therein and without objectively vibrating or shaking the table. This "head motion" may typically consist in a suitable base frame 60 carrying a horizontal crank shaft 85 61. Crank shaft 61 is revolved through the medium of any suitable mechanism, being preferably provided with suitable belt wheels and a suitable balance or fly wheel (not shown). A connecting rod 62 engages 90 the crank of crank shaft 61 and normally extends directly upwardly. A trunnion 63 is mounted on the upper end of the connecting rod which is engaged by two toggles 64. The outer ends of the toggles engage 95 adjustable abutment blocks 65, one of which is adjustably mounted on an extension 66 of frame 60 and the other of which is adjustably mounted on rocker 67. Rocker 67 has suitably upwardly projecting arms 68 engaged by a cross-head 69 adjustably mounted on rod 70. Rod 70 suitably connects with the concentrator table, and a spring 71 suffices to move the table to the left in Fig. 7 and to constantly pull crosshead 69 against 100 the extensions 68 of rocker 67.

In operation, the rotation of crank shaft 61 causes the vertical oscillation of connecting rod 62 and trunnion 63. This causes a horizontal oscillation of rocker 67; and it 105 will be seen from the relative arrangements of the parts that a peculiar motion is imparted to rod 70. When the crank is in its upper position, as shown in Fig. 7, the horizontal movement of rocker 67 is comparatively slow; so that the movement of the rocker at the right hand end of its motion in Fig. 7 will be comparatively slow and the return at that end comparatively easy. When the crank 61 is at the bottom of its 110 motion, the toggles 64 make a sharper angle with each other and the horizontal movement imparted to rocker 67 is comparatively 115 faster. The return at the left hand end of the motion imparted to rod 70 will therefore be very quick; and the resultant motion is one which creates the impression of the table moving down (in the direction of its tail end) and then being jerked back 120 quickly, while the change of motion at the 125 130

upper end of its movement is comparatively smooth and easy. This means that the materials on the table are moved downwardly at a greater speed than they would naturally flow down the table; and this in turn provides that the materials are evenly and smoothly passed over the table in greater quantity in a given time than is otherwise possible, but that the values are easily and efficiently retained on the table and caught in the discharge openings.

In operation, the pulp may be fed to the table inside suitable frames 73 and, overflowing these frames, pass under a spreader bar 74 so that it is evenly spread over the table. The pulp stands thickly enough on the table to cover the riffles thereon; so that the lighter upper strata of the pulp may pass directly down the table over the riffles. The passage of this lighter strata is somewhat outwardly toward the outer edges of the table, and downwardly to compensate for the movement of the heavier material inwardly along the riffles toward the center of the table. This action is somewhat more clearly shown in Fig. 6, where the short heavy arrows designate the paths taken by the heavier materials and the light longer arrows designate the paths taken by the lighter upper strata of materials. The constant vibration of the table serves to move the materials downwardly over it and to allow the adjustment of the heavier and finer particles below and the lighter and coarser particles above. In practice, I have found that the fine heavy metallic particles collect at the bottom, immediately above being the coarse metallic particles; above these the fine light particles accumulate and on top of all are the coarse light particles. The heavier metals being low enough to come into contact with the riffles are moved inwardly toward the concentration line as they pass down the table. Moving downwardly to this line they are then caught in the discharge pipes and pass out of the table in the manner hereinbefore described. The discharge pipes 34 may connect with any suitable collecting means, such as a trough 75. The tailings are passed over the tail end of the table and may be handled in any manner desired.

Having described my invention, I claim:

1. In combination, a longitudinally reciprocating separator table adapted to separate materials both vertically and horizontally and to concentrate and move the heavier materials along and below a concentration line, a relatively thin horizontal strata separator member projecting against the flow of material along the concentration line, and outlet means communicating with the space beneath said member.

2. In combination, a longitudinally reciprocating and longitudinally inclined sepa-

rator table adapted to separate materials both vertically and horizontally and to concentrate and move the heavier materials along and below a concentration line and comprising a thin flat horizontal strata separator member projecting toward the upper end of the table against the movement of material along the concentration line and spaced above the table surface, and outlet means communicating with the space below said separator member to carry off the material separated by said separator member.

3. In combination, a longitudinally reciprocating and longitudinally inclined separator table adapted to separate materials both vertically and horizontally and to concentrate and move the heavier materials along and below a concentration line and comprising a thin flat horizontal strata separator member projecting toward the upper end of the table against the movement of material along the concentration line and spaced above the table surface, outlet means communicating with the space below said separator member to carry off the material separated by said separator member, and a dam arranged adjacent to said outlet means and extending above the table surface on the side of the outlet means toward the upper end of the table.

4. In combination, a longitudinally reciprocating and longitudinally inclined separator table adapted to separate materials both vertically and horizontally and to concentrate and move the heavier materials along and below a concentration line and comprising a thin flat horizontal strata separator member projecting toward the upper end of the table against the movement of material along the concentration line and spaced above the table surface, and outlet means communicating with the space below said separator member to carry off the material separated by said separator member, and a shelf extending over the table surface and spaced above the same adjacent to the said separator member, and means for supplying water on the top of said shelf.

5. In combination, a longitudinally reciprocating and longitudinally inclined separator table adapted to separate materials both vertically and horizontally and to concentrate and move the heavier materials along and below a concentration line and comprising a thin flat horizontal strata separator member projecting toward the upper end of the table against the movement of material along the concentration line and spaced above the table sur-

face, and outlet means communicating with the space below said separator member to carry off the material separated by said separator member, and a shelf extending over the 5 table surface and spaced above the same to the rear of the said separator member, means for supplying water on the top of said shelf, and confining walls for directing such water to the outlet means and to the space 10 beneath said shelf.

6. In combination, a longitudinally reciprocating and longitudinally inclined separator table adapted to separate materials both vertically and horizontally and to concentrate and move the heavier materials 15 along and below a concentration line and separator means arranged on said concentration line and comprising a thin flat horizontal strata separator member projecting 20 toward the upper end of the table against the movement of material along the concentration line and spaced above the table surface, and outlet means communicating with the space below said separator member to 25 carry off the material separated by said separator member, said dam having its top approximately as high as the strata separator member.

7. In combination, a separator table having a series of riffles thereon leading longitudinally of the table and diagonally toward the longitudinal concentrating line, said table being inclined downwardly toward its discharge end, and separator means arranged on said concentrating line and comprising a thin flat horizontal strata separa- 30

tor plate projecting its thin edge toward the upper end of the table against the movement of material along said concentrating line, said plate being spaced above the table 40 surface a distance less than the height of the riffles on the table.

8. In combination, a separator table having a series of riffles thereon leading longitudinally of the table and diagonally toward a longitudinal concentrating line, said table being longitudinally inclined, a separator means arranged on said concentrating line, comprising a thin flat horizontal strata separator plate projecting its thin edge to- 45 toward the upper end of the table and against the movement of material along said concentrating line, said plate being spaced above the table surface a distance less than the height of the riffles on the table, a wedge 50 shaped box having a sharp end projecting toward the upper end of the table against flow of materials along the concentrating line, the interior of the box being in communication with the space beneath the separator plate, said table being provided with outlet aperture in the bottom of the box and a dam over which material passes from beneath the separator plate to said outlet aperture. 55

In witness that I claim the foregoing I have hereunto subscribed my name this 26th day of March, 1912.

JOHN F. ISBELL.
